ABSTRACT

Opposed straightening rolls are mounted within a U-shaped frame, their axes being parallel and at an angle relative to the longitudinal axis of the object to be straightened. One of the rolls is segmented into three separate rollers with the axes of the outer rollers eccentric to the axis of the center roller and adjustable along an arc. The points of contact between the rollers and workpiece are arranged to define a plane containing the longitudinal axis of the workpiece.

FIG. 1

FIG. 2

FIG. 3

MACHINE FOR STRAIGHTENING ELONGATED OBJECTS

This invention relates to straightening devices, and more particularly to equipment for straightening elongated workpieces such as rods or pipes.

Straightening equipment of the type contemplated, generally employs opposed straightening rolls, rotating about longitudinal axes which are at an angle to the longitudinal axis of the workpiece. The rolls on one side may be divided into three rollers, each mounted upon parallel axes, with the outer rollers being eccentrically mounted and adjustable along an arcuate path, relative to the central roller.

Experience indicates that the straight-edges used with such equipment must be frequently replaced due to excessive wear. Attempts to replace them with supporting rollers have failed to produce satisfactory results. On two-roll machines, such as disclosed for example in German Offenlegungsschrift DT-OS No. 1,910,879, it was impossible to provide a satisfactory solution to the rapid wear of the straight-edges. Replacing the straight-edges with supporting rollers created new problems, particularly when working on high-strength small diameter workpieces. Also, thin workpieces are not properly guided and tend to wander from the proper path through the equipment.

Some progress towards straightening without a straight-edge, although it is not a complete solution, is suggested in German Auslegeschrift DT-AS No. 2,113,713. In this disclosure, particularly large supporting rollers provide a long narrow guidance cap for the workpiece, between two bottom outer rollers and the top roll. Here again, however, considerable transverse forces are produced by the one-piece hyperbolic roll that is used. These forces must be absorbed by the supporting rollers.

The present invention uses a unique arrangement of a segmented roll having three rollers to reduce or eliminate the forces which create excess wear. This arrangement positions the points or lines of contact between the three rollers and the workpiece such that they lie substantially within a plane which also contains the longitudinal axis of the workpiece. To effect this, the two outer rollers are displaced in relation to the central roller, towards the workpiece, so that the centers of the three rollers and the longitudinal axis of the workpiece define a plane. Since the rollers and workpiece are of circular cross section, if the line joining the centers of the three rollers lies in the same plane with the longitudinal axis of the workpiece, the points or lines of contact will lie in the same plane.

The two outer rollers, with their points of contact with the workpiece, are the corners of the triangle of bending and, according to the invention, they act as straightening rolls. The forces applied by the outer rollers to the work-piece are, at least theoretically, pure bending forces and have no detrimental components such as transverse forces. The forces applied by the rollers to the workpiece all lie in the plane which includes the centers of the rollers and the workpiece, and they are all theoretically absorbed by the second roll, the center of which lies in the same plane. Straightening with a divided hyperbolic roll according to the invention is basically a problem of planes, and any straight-edge serves merely as a guide subjected to a minimum of wear. Because of the reduced pressure of the work-

piece upon such a straight-edge, synthetic materials may be used along the working edges. In fact, the entire straight-edge may be made of synthetic material.

It is an object of the invention to provide an improved straightening device.

Another object of the invention is to provide a straightening device which creates a minimum of wear upon the guiding straight-edges.

Another object of the invention is to provide a straightening device having improved spring characteristics and ease of roll adjustment.

In accordance with a particular embodiment of the invention, straightening equipment for elongated workpieces is provided with opposed straightening rolls having

their axes positioned at an angle to the longitudinal axes of the workpiece. One of the straightening rolls is segmented into three separate rollers mounted on parallel axes, the two outer rollers being mounted eccentrically in relation to the central roller and being adjustable in relation thereto, along an arc. The points of contact between the rollers and the workpiece are arranged to lie in the same plane as the longitudinal axes of the workpiece.

For a better understanding of the present invention, together with other and further objects thereof, reference is had to the following description taken in connection with the accompanying drawings, and its scope will be pointed out in the appended claims.

In the drawings:

FIG. 1 is a front elevation of a straightening unit according to an illustrative embodiment of the invention;

FIG. 2 is a horizontal section through the unit shown in FIG. 1, at the level of the straightening gap; and

FIG. 3 is a plan view of FIG. 2.

FIG. 1 illustrates a straightening machine having a main frame 1 with a table 2 and two side members 3, 4 extending upwardly therefrom to define a U-shaped gap. Apertures 11 and 12 are provided in the diagonally opposite lateral faces of the side members 3, 4 so

that the workpiece may pass diagonally through the straightening machine. A segmented top straightening roll 5 is mounted in the side members 3, 4 within the gap, and is divided into three parts, or rollers, 5a, 5b, 5c. A bottom straightening roll 6 is mounted in journals

7 directly below top roll 5. The journals 7 run in a roll holder 8 that is mounted to the table 3 in a vertically adjustable manner. A threaded shaft, hydraulic system, or other means may be provided for this adjustability. Straight-edges are provided approximately along the path of the workpiece between the top and bottom rolls, for the purpose of guiding the workpiece. For reasons of clarity, only a rear straight-edge 9, with wearing edges 9a, 9b, is shown. The straight-edge 9 has a recess 10 for bottom roll 6.

Outer rollers 5a, 5c are eccentrically mounted relative to center roller 5b and to adjust for sag or bowing of the workpiece, adjusting mechanisms 13, 14 are provided. These mechanisms permit the raising or lowering of the outer rollers along a slightly curved path.

The position of a workpiece 15 relative to the rollers 5a, 5b, 5c is seen in FIGS. 2 and 3. Center lines 16, 17 show that the two outer rollers 5a, 5c are mounted eccentrically of the center roller 5b, the outer rollers being displaced towards the workpiece 15 which advances diagonally through the straightening machine.

This establishes points of contact 20, 21, 22 directly below the center lines of the relevant rollers, i.e. contact point 20 lies vertically below center line 16,

contact point 21 lies vertically below center line 18, and contact point 22 lies vertically below center line 17. The plan view of FIG. 3 shows clearly that contact points 20, 21, 22 lie vertically under the roller centers and in the same plane as the dotted center line 23 of work-piece 15. Center line 23 also represents the straightening plane.

Depending upon the particular job, all three rollers may be driven by a driving wheel 24; the central roller being driven directly and the two outer rollers by planetary drives. Typical design details for driving the outer rollers appear in aforesaid German Auslegeschrift DT-AS No. 2,113,713. Bottom roll 6 may be driven by a motor via a cardan shaft and transmission. Roll holder 8 may have a bearing adapted to rotate about a vertical axis passing through the center of bottom roll 6 and/or hydraulic support means for the said holder.

If outer rollers 5a, 5c are lowered to a sufficiently great extent, the workpiece can be prevented from coming into contact with center roller 5b. This enables the machine to execute "free bends". Embossing or polishing can be carried out by raising the outer rollers 5a, 5c.

The hyperbolic form of the straightening roll is advantageous; however, as noted above the main defect of this hyperbolic form is the production of transverse forces. In accordance with the invention, the outer rollers 5a, 5c of the segmented roll 5 are provided with convex surfaces, while the inner roller 5b is provided with a concave surface. Experience with this arrangement indicates that the straightening effects are comparable to those achieved with conventional 2-roll machines.

It will be seen that with the structure of this invention, one adjusts for the sag in the workpiece by merely rotating the axes of outer rollers 5a and 5c in order to modify their eccentricity relative to the central roller 5b. There is no change in the position of the central roller 5b nor is there any rotation of the central roller about a vertical axis.

It will be appreciated that rotation of the outer rollers 5a and 5c along an axis about the longitudinal axis of center roller 5b theoretically makes it impossible to fulfill the requirement that the points of contact lie in a plane with the longitudinal axis of the workpiece. In practice, however, the deviation from the ideal geometrical form is minimal and not significant. In effect, there is a long lever arm relationship involved so that the minimum angular displacements in the vicinity of dead center do not detrimentally effect the substantially "planar" relationship between the various points of contact and the workpiece axis.

Although the invention may be practiced in embodiments wherein the lower roll is segmented, rather than the upper roll, it has been found advantageous to employ the basic structure illustrated in the embodiment of FIG. 1. With this structure, it is not necessary to rotate the central roller 5b about a vertical axis and accordingly it can be mounted directly to rigid vertical members 3, 4 of the machine 1. This eliminates the need for a cross-bar joining the side members and/or means for radially adjusting the top roll 5.

With the axis of the center roller 5b fixedly established, the straightening gap is controlled by vertical positioning of the bottom roll 6 only. Of course, the straightening gap is adapted to the diameter of the workpiece being handled and variations in the straightening gap cause a displacement of the longitudinal axis

of the workpiece. For example, when changing from a larger to a smaller diameter workpiece, the center line of the workpiece is displaced in an upward direction. This requires commensurate displacement of the input and output channels. However, as the diameter decreases, the sag required for straightening increases and the ends of the workpieces projecting beyond the rolls, drop. This leaves only the difference in displacement and sharply reduces the necessary adjustability of the input and output channels as a whole.

Those skilled in the art are familiar with the "pear-shaped" deformation of the ends of workpieces, created as they enter or leave straightening machines. It is believed that the spring in the frame of the machine is basically responsible for this deformation. By rigidly mounting the axis of the top roll, with no provision for angular adjustment, one is able to achieve a particularly stiff machine, i.e. one having a sharp characteristic spring curve for the frame of the machine. Indeed, in the absence of a cross-bar across the vertical members 3-4, these members must have a relatively large cross-section; however, this increase in cross-section is easily offset by the elimination of the cross-bar with its attendant weight. Still further, increased mass in the vertical members 3, 4 has the additional effect of reducing their elasticity and improving the stiffness characteristic of the entire unit.

While there has been described what is at present considered to be a preferred embodiment of this invention, it will be obvious to those skilled in the art that various changes and modifications may be made therein without departing from the invention, and it is aimed, therefore, in the appended claims to cover all such changes and modifications as fall within the true spirit and scope of the invention.

I claim:

1. A straightening machine for elongated workpieces comprising: opposed straightening rolls having axes positioned at an angle to the longitudinal axis of the workpiece, one of said straightening rolls including three rollers mounted on parallel axes, the two outer rollers being mounted eccentrically in relation to the center roller and being adjustable in relation thereto along an arc, the points of contact between said rollers and said workpiece being in a plane with the longitudinal axis of the workpiece.

2. A straightening machine according to claim 1, wherein said two outer rollers have convexly arched peripheries and said center roller has a conversely arched periphery.

3. A straightening machine as defined in claim 1, wherein said opposed straightening rolls are positioned vertically, one above the other; said three rollers comprising the upper one of said rolls.

4. A straightening machine as defined in claim 3, wherein said rolls are positioned between two vertical support members, the rollers of said upper roll being journaled directly in said support members.

5. A straightening machine as defined in claim 4, wherein said vertical support members are joined only at the bottom.

6. A straightening machine as defined in claim 4, wherein said two outer rollers have convexly arched peripheries and said center roller has a conversely arched periphery.

7. A straightening machine as defined in claim 3, including means for vertically adjusting the position of the lower one of said rolls.

8. A straightening machine as defined in claim 1, including a roll disposed generally opposed to said three

roller roll and having a convexly arched periphery.
